UNITED STATES PATENT OFFICE.

ARTHUR F. CASE, OF CLEVELAND, OHIO, ASSIGNOR TO THE WELLMAN-SEAVER-MORGAN COMPANY, OF CLEVELAND, OHIO, A CORPORATION OF OHIO.

MATERIAL-HANDLING APPARATUS.

Application filed March 31, 1921. Serial No. 457,248.

To all whom it may concern:

Be it known that I, ARTHUR F. CASE, a citizen of the United States, residing at Cleveland, in the county of Cuyahoga and State of Ohio, have invented a certain new and useful Improvement in Material-Handling Apparatus, of which the following is a full, clear, and exact description.

The present invention relates to material handling apparatus, and has particular reference to boat loading apparatus of the type wherein material such as coal is conveyed or otherwise caused to travel outwardly along a boom or equivalent member to a down-

wardly extending collapsible chute adapted to be extended into the hatch of a boat and to be provided at its lower end with a trimmer for distributing the material in the hatch. Boat loading apparatus having parts

constructed and arranged as above stated, are commonly utilized in connection with various styles or kinds of apparatus, such, for example, as a car dumper wherein provision is made for elevating and tilting a

car to dump the contents into a suitable receiving part which delivers it to the chute referred to above. They are also commonly employed on so-called towers movable along the edge of a loading pier in which case the material is generally delivered to the conveyor of the boom from a hopper in which the material is dumped from a car, such as a transfer car, movable along the pier on an upper level.

In boat loading apparatus of the type referred to above, the chute which is adapted to be extended into the hatch of the boat and which carries the trimmer is generally collapsible, or otherwise constructed so that the delivery end can be raised and lowered, and it is pivoted on the boom or other member supporting it so that it can be tilted not only for the purpose of permitting material to be distributed uniformly about the hatch, but in order that the material passing down the chute will more or less slide down along the rear wall, this being desired in order that the material may be most effectively diverted at the trimmer and discharged laterally therefrom.

Generally the chute is pivoted on an axis so that it may be swung inwardly and out-

wardly with reference to the edge of the pier, but the lateral swinging is usually accomplished not by swinging the entire chute, but by bending or flexing it, which is rendered possible by reason of the fact that the chute is formed of sections. The swinging of the chute inwardly and outwardly, the flexing of the chute to bend it laterally, and also the raising and lowering of the chute are accomplished by means of cables connected to the lower end of the chute, and passing about motor driven drums supported on the boom or equivalent device from which the chute is hung.

The principal object of the present invention is to reduce the number of motors and to simplify the mechanical and electrical apparatus utilized in swinging or shifting the chute in the directions and for the purpose stated above.

The invention may be briefly summarized as consisting in certain novel combinations and arrangements of parts and details of construction which will be described in the specification and set forth in the appended claims.

In the accompanying sheets of drawings wherein I have shown an embodiment of the invention which operates very effectively, Fig. 1 shows a tower movable along the edge of a pier, and having delivery and trimming apparatus with which my invention is incorporated; Figs. 2 and 3 are views showing in side elevation the outer end of the boom with the delivery chute swung inwardly in Fig. 2, and swung outwardly in Fig. 3; Fig. 4 is a similar view, showing the chute in vertical position, and by dotted lines showing it collapsed; Fig. 5 is a view looking toward the outer end of the boom, but showing the chute flexed or bent laterally, by full lines in one direction, and by dotted lines in the opposite direction; Fig. 6 is a side view of the outer end of the boom, showing the chute collapsed and swung upwardly in substantial parallelism with the boom; Fig. 7 is a plan view of a trolley which is mounted on the boom and carrying apparatus utilized in giving the chute the various motions depicted in the preceding figures; Fig. 8 is a sectional view substantially along the line 8-8 of Fig. 7; and Fig. 9

is a sectional view substantially along the line 9—9 of Fig. 7, looking in the direction indicated by the arrows.

Referring now to the drawings, 10 represents a boom or arm adapted to be extended out from a suitable support over a boat to be loaded. The material to be loaded into the boat is conveyed or otherwise moved out along the boom to a delivery chute 11 which 10 is hinged or pivoted at 12 to the outer portion of the boom to swing on a horizontal axis inwardly and outwardly from the vertical position. This chute which is adapted to be extended down into the hatch of 15 the boat as already stated, is in this instance composed of telescopic sections so that it can be collapsed or extended as desired.

At the lower end of the delivery chute is a trimmer by which the material is adapted 20 to be distributed about the hatch of the boat. In this case a rotary trimmer 13 is contemplated, adapted to be rotated about the axis of the chute, and provided with an elbow 14 by which the material passing 25 down the chute is diverted laterally, and provided also with a swinging delivery member 15 which carries a distributing belt 16 adapted to be driven by a motor carried by the trimmer, but not shown. As the invention does not reside in the details of the 30 trimmer, further explanation thereof is believed to be unnecessary.

The boom or arm 10 may be of any suitable construction, and the material may be 35 conveyed or moved along the boom in different ways, but in this instance the boom is provided with a conveyor indicated at 17, the outer end of the conveyor being just above the chute 11, as shown in the drawings. The boom or arm may be in the form 40 of an inclined pan or chute along which the material passes by gravity, but the member 10 will be hereinafter referred to as a boom which may or may not be provided with a 45 conveyor to positively move the material outwardly to the chute 11.

The boom may be supported on a stationary structure such as a car dumper frame, or on a movable structure such as the frame 50 18 of a tower which I have shown in Fig. 1, for the purpose of illustrating one of the several kinds of apparatus with which the invention has utility. The tower 18 is in this instance movable along the lower part 55 of a pier indicated at 19, and alongside of which a boat 20 to be loaded is positioned. The boom may be connected to the tower or other support in different ways, but is always capable of being swung up and down, 60 hoisting mechanism 21 being shown for that purpose.

The manner in which material is delivered to the boom, will, of course, depend upon the type of machine with which the 65 boom is used, but in this instance the ma-

terial is adapted to be delivered onto the conveyor 17 of the boom by a chute, or equivalent member 22 carried by the tower and adapted to receive material from the delivery end or spout 24 of a hopper 25 carried 70 by the upper structure 26 of the pier. A car is adapted to be moved out along the pier, and to dump material into the hopper 25, a number of which will be provided along the upright structure so that the tower 75 can receive coal from any of them, depending upon its position on the pier.

The parts so far described are more or less common in this art, and need not be further referred to except in explaining the 80 location, structure and purpose of the parts more directly involving my invention.

As already stated, the present invention resides in the improved mechanism for extending and collapsing the chute, for swinging 85 the chute from vertical position inwardly, as shown in Fig. 2, outwardly, as shown in Fig. 3, and for bending the chute laterally in either direction from vertical position as shown in Fig. 5, and for otherwise shifting the chute, as for example, to the position shown in Fig. 6, should it be desirable to move the chute to the position there shown, as for example, to clear the rigging of a boat to be loaded. 95

A series of cables have heretofore, and by the present invention are utilized for shifting or moving the chute, but heretofore the apparatus for winding in or paying out the cables was mounted in fixed position on 100 the outer portion of the boom, and in any installation having provision for swinging the chute inwardly and outwardly, and also flexing it laterally, four motors and four separate drums have heretofore been employed. 105

In accordance with the present invention, the mechanism for shifting the chute is mounted on a trolley 27, most clearly shown in Figs. 7 and 8. This trolley is provided 110 with wheels 28, and in this instance is adapted to travel along the rails 29 and 30 carried by the outer portion of the boom 10. The rails 30 are guard rails located above the rails 29, and the wheels 28 have double 115 flanges so that the trolley will be held onto the boom between the upper and lower rails, regardless of the position to which the boom may be swung. On this trolley two motors are provided, one a traversing motor 31 to 120 shift the trolley along the boom. This motor 31 is connected by gears 32 and by self-locking worm gearing, not shown, but contained in a gear case 33^a, to a shaft 33 having pinions 34 adapted to engage racks 35 125 carried by the boom inside the rails 29, as best shown in Fig. 8. The motor shaft may be provided with a brake 36 which may be an electric brake for the purpose of quickly stopping the motor, though a braking action 130

is not required to hold the trolley in any given position on the boom since the self-locking worm gearing serves this purpose.

The second motor carried by the trolley 5 is shown at 37, the purpose of this motor being to drive simultaneously or separately, two rope drums 38 and 39, supported on opposite sides of the center line of the trolley, as shown in Figs. 7 and 8. The motor 10 shaft is connected by flexible couplings indicated conventionally at 40, to a pair of shafts 41, each of which is adapted to be clutched by any suitable clutch mechanism indicated at 42, such, for example, as a magnetic clutch, to a sleeve 43 (see Fig. 9) carrying a brake, indicated conventionally at 44, and a pinion 45, as clearly shown in Figs. 7 and 9. The pinions 45 engage gears 46 on countershafts 47 provided with pinions 48 engaging gears 49 on the shafts of the two drums 38 and 39. It will be seen from the mechanism so far described, that the trolley as a whole can be moved along the boom in either direction by the motor 25 31, and that both drums 38 and 39 can be simultaneously driven by the motor 37 or either can be driven independently of the other and in either direction (the motors 31 and 37 being, of course, reversing motors) 30 by selectively operating the clutches 42 and the brakes 44.

In Fig. 9 I have shown conventionally a standard type of magnetic clutch 42, the main part 42^a, which is keyed to the shaft 35 41, carrying an energizing winding 42^b, and the armature 42^c being carried by the sleeve 43, and being adapted to be magnetically attracted, and therefore clutched to the body 42^a of the clutch when the body is energized. 40 Any suitable type of brake 44 may be utilized, but the details of the brake I have not shown as they form no part of the present invention, but in practice I prefer to use any of the well known magnetic brakes 45 adapted to be set by a spring and released by a magnetic winding which can be energized and de-energized at the same time that such winding 42^b is energized and de-energized.

50 Referring now to Figs. 2 to 6, it will be seen that the chute is swung inwardly and outwardly, and tilted or flexed laterally, and it is extended or collapsed by four cables in two sets, one set of two cables, designated 55 50 and 51 being connected to one side of the lower part of the chute, and adapted to be wound onto and unwound from the drum 38, and the other two similar cables (not shown, except in Fig. 5, where the cable 60 designated 51^a and corresponding to the cable 51 is shown) being similarly connected to the opposite lower side of the chute 11, and being adapted to be wound onto and unwound from the drum 39.

65 Referring now to Figs. 2, 3 and 4, it will

be observed that one end of the cable 50 is connected at 52 to the rear end of the trolley 27. From this point the cable passes inwardly along the boom, downwardly, and then outwardly around deflecting sheaves 70 53, 54 and 55 carried by the boom; then downwardly and around a sheave 56 carried by the lowermost section of the chute 11, then upwardly around a deflecting sheave 57 carried by the boom, inwardly, 75 upwardly about deflecting sheaves 58 and 59, and outwardly around drum 38, the cable passing over the upper part of the drum, as shown in Fig. 2. The other cable 51 is attached at 60 to the outer or forward 80 end of the trolley, and from the latter extends forwardly to a deflecting sheave 61 at the forward end of the boom, then downwardly around sheave 62 carried by the lowermost section of the chute 11 adjacent 85 the sheave 56, then upwardly around a deflecting sheave 63 carried by the boom alongside the sheave 61, and then inwardly along the boom and around the drum 38, this cable passing under the lower part of the 90 drum, in other words, oppositely with respect to the cable 50.

The other two cables corresponding to the cables 50 and 51 are connected to the trolley, pass about similar sheaves, and pass 95 onto the drum 39 in precisely the same way as the cables 50 and 51 are connected to the trolley and pass around the deflecting sheaves described and are wound onto the drum 38.

100 The machine is operated in the following manner. If it is desired to collapse or extend the chute 11 without swinging or flexing it, the trolley 27 is stationary. To extend the chute, i. e. to lower the trimmer, the motor 105 is connected by the clutches 42 to both drums 38 and 39, and the motor 37 is operated to simultaneously rotate both drums so as to pay out all four cables, the brakes 44 then being released. To collapse the chute 110 the motor is operated so as to rotate the drums in the opposite direction, and wind in all four cables. To swing the chute either inwardly or outwardly, the drums are not rotated, but the trolley is shifted inwardly or outwardly as the case may be. For example, should it be desired to swing the chute from the vertical position shown in Fig. 4, inwardly to the position shown in Fig. 2, as when it is desired that the coal 115 be distributed in the inner part of the hatch, with both brakes 44 set, the trolley is simply moved outwardly from the position shown in Fig. 4 to the position shown in Fig. 2. This in effect pays out the cables 51 and 120 pulls in on the cables 50.

Likewise, should it be desired to swing the chute outwardly to the position shown in Fig. 3, as when it is desired to trim the outer part of the hatch, it is simply necessary to 130

move the trolley by operating the motor 31 to the position shown in Fig. 3. In a similar manner, a chute can be swung outwardly substantially into alignment with 5 the boom, as indicated in Fig. 6, but the limits of inward and outward movement indicated by Figs. 2 and 3 indicates the range of inward and outward swinging movement necessary to trim the inner and outer parts 10 of the hatch.

Should it be desired to bend the chute laterally in either direction so that the major portion of the coal will pass down what is in effect the rear wall of the chute when 15 the forward and rear parts of the hatch are being trimmed, as indicated in Fig. 5, it is only necessary to operate one or the other of the two drums 38 and 39 with the other held stationary so as to wind in some- 20 what, the cables on one side of the chute.

Thus by two drums and the trolley, and by two motors, one a trolley reversing motor and the other a drum operating motor, all the necessary movements can be given to 25 the delivery chute 11, and therefore the control of the chute is simplified and the number of operating parts is reduced.

I believe it is broadly new to control a delivery chute such as that forming a part 30 of a boat loading apparatus through the medium of a movable trolley to which the controlling cables are connected and carrying the winding and unwinding mechanism for the cables, irrespective of the part on 35 which the trolley is mounted.

While I prefer that the trolley be mounted on the boom or other part carrying the chute, and have so shown and described it in this application, it might be advisable to lighten 40 the boom or to relieve it of the chute controlling mechanism, and to mount the trolley on the tower or supporting framework carrying the boom. In such case the cables would be carried inwardly along the boom 45 through the medium of suitably positioned guide sheaves, and will be connected to the trolley and to the drums, substantially as herein shown.

Having described my invention, I claim: 50

1. In a material handling apparatus, a chute, a member supporting the chute and adapted to deliver material thereto, and means for swinging the chute laterally comprising a movable trolley, and connections 55 between the trolley and the chute.

2. In a material handling apparatus, a chute, a member supporting the chute and adapted to deliver material thereto, means for extending and collapsing and shifting 60 the chute so as to move the lower part thereof laterally with respect to the upper part comprising a trolley having winding and unwinding means, and cable connections with the chute.

3. In a material handling apparatus, a

supporting structure, a boom extending therefrom, a chute supported by the boom and adapted to receive material therefrom, and means for controlling the chute comprising a trolley mounted on one of said parts and having suitable cable connections with the chute. 70

4. In a material handling apparatus, a supporting structure, a boom extending outwardly therefrom, a movable trolley mounted on one of said parts, a chute movably supported by the boom, and means mounted on the trolley and connected to the chute for extending and collapsing it, and for swinging the chute in various directions. 75

5. In a material handling apparatus, a chute, a member supporting the chute and adapted to deliver material thereto, and means comprising a trolley on said member for swinging the chute. 80

6. In a material handling apparatus, a chute, a member supporting the chute and adapted to deliver material thereto, means comprising drums and cables adapted to be wound onto and from the drums and connected to the chute for extending, collapsing and shifting the chute, and means carrying the drums and movable along said member carrying the chute. 90

7. In a material handling apparatus, a chute, a member supporting the chute and adapted to deliver material thereto, means for controlling the chute comprising a trolley movable along said member, cables connected to the chute, and winding means for 100 the cables carried by the trolley.

8. In a material handling apparatus, a chute, a member supporting the chute and adapted to deliver material thereto, a trolley movable along said member, and means 105 carried by the trolley and connected to the chute for extending and collapsing the chute, for swinging it inwardly and outwardly, and for moving the lower end of the chute laterally in either direction. 110

9. In a material handling apparatus, a boom, a chute pivoted to the outer portion of the boom adapted to receive material from said boom, a trolley movable along the boom and having means for propelling the trolley along the boom and carrying cable winding and unwinding means for extending and collapsing and shifting the chute. 115

10. In a boat loading apparatus, a delivery boom, a chute pivoted at the outer portion of the boom and adapted to receive material from the boom, a trolley carried by the boom and movable along the same, drums carried by the trolley, and cables passing about said drums and connected to 120 the chute. 125

11. In a boat loading apparatus, a delivery boom, a collapsible chute pivotally supported at the outer portion thereof and adapted to receive material from the boom, 130

the lower part of the chute having a trimmer, a trolley movable along the boom, and cables connected to opposite sides of the lowermost section of the chute and operatively connected to the trolley.

12. In a boat loading apparatus, a delivery boom, a chute pivotally supported at the outer end of the boom, a trimmer at the bottom of the chute, cables for raising and 10 lowering the trimmer and lower end of the chute, and for shifting the chute, and means for taking in and paying out the cables comprising a trolley, winding and unwinding mechanism connected to the cables and carried by the trolley, and means for shifting the trolley along the boom.

13. In a boat loading apparatus, a delivery boom, a telescopic chute pivotally supported at the outer portion thereof, adapt-

ed to receive material from the boom, and 20 provided at its lower end with a trimmer, a trolley movable along the boom, cables connected to opposite sides of the lowermost portion of the chute, to the boom and to winding and unwinding mechanism carried 25 by the trolley to cause the collapsing or extending of the chute and to swing it inwardly, outwardly or laterally.

14. In a material handling apparatus, a supporting structure, a boom extending 30 therefrom, a chute supported by the boom and adapted to receive material therefrom, and means for controlling the chute comprising a movable trolley on the boom, and connections between the trolley and chute. 35

In testimony whereof, I hereunto affix my signature.

ARTHUR F. CASE.
